UNITED STATES PATENT OFFICE.

WILLIAM L. COUTURE, OF SAN FRANCISCO, CALIFORNIA, ASSIGNOR OF ONE-FOURTH
TO JOHN J. REDMOND, OF SACRAMENTO, CALIFORNIA.

JACK.

Application filed May 31, 1921. Serial No. 473,656.

To all whom it may concern:

Be it known that I, WILLIAM L. COUTURE, a citizen of the United States, residing at San Francisco, in the county of San Francisco and State of California, have invented new and useful Improvements in Jacks, of which the following is a specification.

This invention relates to improvements in jacks and more particularly to that type in which the base and lifting member are both extensible from the body portion.

The primary object of the invention is to provide a jack of the character described which will be exceptionally quick acting, easy to operate and reliable in operation, the jack being comparatively simple as to construction, formed of few parts, inexpensive and capable of being readily and easily assembled and disassembled.

20 A further object is to generally improve lifting jacks of the character described so as to render them easier and cheaper to make, more certain and reliable in operation, strong, durable and capable of greater lifting power, with the employment of but a few simply constructed parts, whereby the jack may be made comparatively small and light as to weight.

The invention possesses other advantages 30 and features some of which, with the foregoing will be set forth at length in the following description where I shall outline in full that form of the invention which I have selected for illustration in the drawings accompanying and forming a part of the present specification. In said drawings I have shown one form of the construction of my invention, but it is to be understood that I do not limit myself to such form since the 40 invention as expressed in the claims may be embodied in a plurality of forms.

Referring to the drawings:

Figure 1 is a side elevation of the jack of this invention.

45 Figure 2 is a vertical sectional view.

Figure 3 is a horizontal sectional view taken on line 3—3 of Fig. 2 showing the wrench in position for operating the jack.

In the embodiment of the invention shown 50 in the accompanying drawing the jack is made up of an upright body portion or standard 5 being squared at its lower end as at 6. A lifting member 7 is extensible from one end of the standard and a base member 55 8 is extensible from the other end. Means 9

is provided for extending and withdrawing the members 7 and 8.

The standard has a screw threaded bore 10 in which is received the screw threaded stem 11 of the member 7. The lower portion of the standard has the screw threads 12 of its bore oppositely extended and receives the screw threaded stem 13 of the base 8. When the member 7 is in withdrawn position and the base 8 is engaged with the lower end of the standard, the opposed ends of the stems 11 and 13 are spaced from one another slightly. These stems are bored as at 14 so that the bores aline and a rod 15, which rod is angular in cross section is slidably but 70 non-rotatably received in the bores 14. The base member may be provided with spurs 16 on its under face to prevent slipping and turning thereof. The lower end of the standard is enlarged as at 17 to provide a 75 firm bearing for the base.

The means 9 for operating the jack comprises two independent ratchet devices 18 and 19 respectively, one for extending the members 7 and 8 and the other for withdrawing said members. The device 18 comprises a ratchet wheel 20 with a square or angular opening 21 centrally thereof and teeth 22 on its upper face. This wheel slips over the standard, receiving the angular portion 6 thereof in the opening 21 so as to prevent turning of the wheel on the standard, the lower side of the wheel being engaged with the enlarged portion 17. A rotary ratchet wheel 23 is provided with a 85 circular opening 24 loosely receiving the standard 5. This wheel has ratchet teeth 25 on its lower face for cooperation with the teeth 22. A nut like boss 26 extends upwardly from the wheel 23 and is adapted to have a wrench 27 engaged therewith so as to provide for rotation of the wheel upon the standard. When the wrench is engaged and turned so as to cause the wheel 23 to turn, the standard is rotated and by reason of the 90 oppositely threaded stems on the members 7 and 8 the said members will be extended from opposite ends of the standard. The wrench may be moved in the opposite direction to obtain a new purchase and leverage 105 as in working the ordinary ratchet tool.

The device 19 comprises a ratchet wheel 28 mounted on the portion 6 of the standard so as to be held against rotation on the standard. A rotatable ratchet wheel 29 cooperates 110

with the one 28 and has a nut like boss 30. These wheels are identical in construction with the wheels of the device 18. The lower wheel 28 rests upon the upper side of the boss 26 of the wheel 23. The wheels 23, 28 and 29 are vertically movable upon the standard and so move when the wrench is reversed and the wheels 23 and 29 idle on the standard. The device 19 when operated rotates the standard so as to withdraw the members 7 and 8. To prevent rattling and insure proper cooperation of the ratchet wheels, said wheels are yieldingly held engaged by a helical expansion spring 31. This spring surrounds the standard 5 and engages a plate 32 mounted on the upper side of the wheel 29. The upper end of the spring is housed in a collar 33 which is adjustably held upon the standard by a set screw 34.

The wheels 20, 23, 28 and 29 also the collar 33 plate 32 and spring 31 are capable of being readily and easily removed from the standard. To do this the member 7 is unscrewed and withdrawn from the standard and the above named parts may be lifted off of the standard. This facilitates repair and renewal of broken or worn parts. The rod 15 prevents relative turning of the stems and insures simultaneous rotation thereof.

In use, the jack is placed with its base 8 upon a support and the member 6 against the object to be lifted. By fitting the wrench to the wheel 23 and turning to the left the standard will be rotated so as to simultaneously extend the base and member 7. This will quickly lift the jack bodily when the base is mounted on the ground or other immovable supporting surface, and at the same time extend the member 6 relative to the standard, with the result that the lifting action is more quickly effected than is the case with the ordinary jack. To withdraw the base 8 and member 7, or in other words lower the jack, the wheel 29 is turned so as to rotate the standard in the direction which will take in on the stems for the base 8 and member 7. The friction is placed entirely on the screw threads of the stems and of the bore of the standard and as these stems

are relatively long, the friction is distributed whereby the jack may be operated with ease.

I claim:

1. In a jack, a standard having a bore extending longitudinally therein from both ends thereof, said bore being oppositely screw threaded, right and left screw threaded stems engaging in said bore and projecting outwardly from the ends of said standard, a base member on one of said stems, a lifting member on the other stem, a ratchet wheel fixed to the standard, a ratchet wheel rotatable upon the standard and cooperative when the first ratchet wheel, means for turning the first ratchet wheel so as to rotate the second ratchet wheel and standard in one direction and similar ratchet means for rotating the standard in another direction.

2. In a jack, a base member, a lifting member, a rotary standard, means for connecting the lifting member and base to the ends of the standard which means will simultaneously extend the members when the standard is rotated in one direction and simultaneously withdraw said members when the standard is rotated in the other direction, and means for rotating the standard in either direction comprising ratchet wheels fixed to the standard, other ratchet wheels rotatable on the standard and each cooperating with one of the first named wheels, and a member for rotating either of the last named wheels.

3. In a jack, a base member, a lifting member, a rotary standard, means for connecting the lifting member and base to the ends of the standard which means will simultaneously extend the members when the standard is rotated in one direction and simultaneously withdraw said members when the standard is rotated in the other direction, means for rotating the standard in either direction comprising ratchet wheels fixed to the standard, other ratchet wheels rotatable on the standard and each cooperating with one of the first named wheels, a member for rotating either of the last named wheels, and spring means yieldingly holding said wheels together.

WILLIAM L. COUTURE.
